UNITED STATES PATENT OFFICE.

WASHINGTON I. LUDLOW, OF CLEVELAND, OHIO, ASSIGNOR TO THE CLEVELAND WINDOW SHADE COMPANY, OF SAME PLACE.

COMBINED CARPET STRETCHER AND TACKER.

SPECIFICATION forming part of Letters Patent No. 425,137, dated April 8, 1890.

Application filed September 6, 1889. Serial No. 323,191. (No model.)

To all whom it may concern.

Be it known that I, WASHINGTON I. LUDLOW, a citizen of the United States, residing at Cleveland, in the county of Cuyahoga and State of Ohio, have invented new and useful Improvements in Combined Carpet Stretchers and Tackers, of which the following is a specification.

My present invention relates to that class of tools or appliances used for simultaneously stretching and tacking carpets, and the purpose thereof is to provide simple and easily-operated means whereby the carpet may be stretched and its edge brought to the proper position preparatory to the insertion of a tack or fastening, and whereby the fastenings which secure the carpet to the floor may be fed consecutively to the point of insertion by automatic but positive means and driven through the edge of the carpet into the floor by a hammer in the hands of the operator, said hammer acting upon a spring-raised plunger in the head of the stretcher to drive a fastening which is fed automatically through the handle of the implement.

It is also one purpose of my invention to combine with the stretching and tacking implement simple and novel means for automatically feeding forward the fasteners to the stroke of the driver, to provide a stretcher-staff with a detachable tacking and feeding arm, and to simplify and improve the several parts composing the compound implement or tool; and to the ends specified the invention consists in the several novel features of construction and new combinations of parts hereinafter fully set forth and claimed.

In order to enable those skilled in the art to make and use my invention, I will now describe the same in detail, reference being had to the accompanying drawings, in which—

Figure 1 is a side elevation of a stretcher and tacker embodying my invention. Fig. 2 is a horizontal section of the tacking and feeding arm shown in Fig. 1. Fig. 3 is a sectional view of the tacker-head and feeding-arm, showing the construction and arrangement of the driver relatively to the feeder. Fig. 4 is a detail perspective of the separator; and Fig. 5 is a detail perspective of the feeder removed from the tacking and feeding arm, said Figs. 2, 3, 4, and 5 being on an enlarged scale.

In the said drawings, the reference-numeral 1 designates the stretcher staff or pole, which is usually made of wood of any suitable length. It may be provided at one end with claws 2, or other similar devices, and at the opposite extremity is mounted a forked bracket 3, having in each branch or member 5 of the bifurcated end a slot 4, extending from the ends of the fork to a seat 5, formed in each forked extremity. The stretcher-arm 6 is connected to this staff by being inserted between the arms of the fork, its end being provided with outwardly-projecting studs 7, which enter the slots 4 and lie in the seats 5. By this construction the stretcher staff and arm may be readily connected and disconnected to permit the arm to be used separately where the staff is not required and to permit the insertion of the fasteners.

The stretcher-arm 6 is provided with a longitudinal opening of such form and dimensions as to readily admit the insertion of a flat fastener-carrying bar 8. The flat staples 9 are straddled upon the bar, fitting the same closely, but sliding freely thereon. Within the opening in which said bar is introduced lies a feeder 10, composed of a metallic plate 80 bent to inclose the bar 8, and having wings 12 extending from its forward end and lying upon the sides of the bar 8, said wings being bent toward each other in such manner that as the bar 8, with the fasteners mounted thereon, is pushed into the arm 6 the wings will yield and permit their passage, but will spring in against the sides of the bar as soon as the fasteners have passed. Upon the outer faces of the feeder 10 are formed lugs 13, 90 which project through longitudinal slots 14 in the sides of the arm 6, and by means of which the feeder can be pushed forward or retracted.

Upon the forward end of the arm 6 is mounted a tacker-head or driving-head 15, arranged at a suitable angle with the arm. This head is substantially cylindrical in form, and is provided upon its lower end with teeth 16, which are adapted to engage the carpet at 100 or near its edges.

Within the driving-head, which is provided with a longitudinal opening for the purpose, is arranged a driver consisting of a cylindrical body 17, having a collar 18, which engages a shoulder 19 on the interior of the

head to limit the upward movement of the driver, and provided with a flat driving-plate 20, which drops downward until its end lies normally just above the plane of the tops of the staples or fasteners 9, in which position the end of the bar 8 abuts against the lower end of the plug, whereby said bar is prevented from passing beneath and obstructing the driver, while the bar is held in proper position to feed the fasteners successively beneath the driving-plate.

Surrounding the plate 20 is a spiral spring 21, resting against the collar 18 at one end and at the other end against the top of a feeding or separating plug 22, composed of a cylindrical piece of metal entering the lower end of the driving-head and held in place therein by a screw 23. An opening or recess 24, corresponding substantially with the opening 20 in the arm 6, is formed in the cylindrical face of this separator, facing the opening in the arm and extending to a point a little beyond the axial center of the separator. The ends of the separator extend above and below the ends of the recess 24, and through each end or head is cut a central slot 25 of a length and width to allow the free passage of the flat driving-plate 20, which moves in close proximity to or against the flat face of the recess 24.

The feeder 10 is fed forward by an ordinary elastic band 26, passing around the driving-head and looped over the lugs 13, which project through the slots 14 in the arm, one or 35 more of such bands being used, as circumstances may require.

The implement is operated in the following manner: The staples, which are formed of uniform size, or substantially so, form a flat metal strip straddled upon the bar 8, as already described, and the bar is then inserted in the arm 6, the feeder 10 being retracted until the lugs 13 reach the rear ends of the slots 14 or until the wings 12 spring against the flat faces of the bar 8 in rear of the string of staples. The bar 8 being pushed forward until its end enters the recess 24 in the plug 22 and rests against the lower end of the plug, the arm 6 is mounted in the fork 3 of the stretcher-staff 1 by means of the studs 7, which enter the slots 4 in the forked bracket and pass into the seats 5. The claw 2 on the end of the staff is then braced against any convenient support; or it may be hooked into the carpet at a suitable distance from the edge to be tacked, and the arm 6 being turned to form an angle with the staff 1 the head is placed upon the edge of the carpet in such manner that its teeth 16 engage therewith, and the operator then exerts sufficient pressure to bring the arm 6 and staff 1 into the same straight line, or as nearly so as circumstances may require. When the edge of the carpet is in place, a light blow is struck with 65 the hammer upon the cylindrical part 17 of the driver, thereby forcing the flat plate

20 down through the separator 22, a staple being carried with it and driven. The spring 21 immediately restores the driver to place, and the feeder 10, under the tension of the rubber band or bands, immediately advances the string of staples upon the bar 8 and flares the forward staple immediately beneath the driving-plate 20, in readiness for a repetition of the operation. Then the fasteners are exhausted, the bar 8 is removed, and another similar bar, provided with a fresh supply, is substituted.

What I claim is—

1. The combination, in a carpet stretcher and tacker, of a stretcher-arm having at one end a head provided with teeth to engage a carpet, a reciprocating tack-driver confined in said head, a tack-carrying bar in the stretcher-arm, and a spring-impelled tack-feeder embracing and sliding on the tack-carrying bar, and having at one end two converging spring-wings which yield laterally to permit the passage of the tacks on the tack-carrying bar and then spring back in rear of the tacks to advance them, substantially as described.

2. The combination, in a carpet stretcher and tacker, of a stretcher-arm having longitudinal slots and a head provided with teeth to engage a carpet, a reciprocating tack-driver confined in said head, a tack-carrying bar in the stretcher-arm, a sliding tack-feeder embracing the tack-carrying bar having lateral lugs extending through the slots in the stretcher-arm, and provided at its front end with two converging spring-wings which yield laterally to permit the passage of the tacks on the tack-carrying bar and then spring back in rear of the tacks to advance the latter, and a spring connected with the head and the lateral lugs to slide the said feeder, substantially as described.

3. A carpet stretcher and tacker consisting of a stretcher-staff, a hollow stretcher-arm jointed to said staff and having a tubular driving-head provided with teeth to engage the carpet, a tack-separating plug arranged in the driving-head and having a vertical orifice and a lateral or side opening to receive the tacks, a tack-driver having a collar, a spring between the collar and the upper end of the tack-separating plug, a tack-carrying bar abutting the said plug and having a portion extending thereinto to deliver the tacks to the vertical orifice, and a sliding feeder embracing the tack-carrying bar, and having at one end the converging spring-wings which yield laterally to permit the passage of the tacks and then spring back in rear of the latter, substantially as described.

In testimony whereof I have affixed my signature in presence of two witnesses.

WASHINGTON L. LUDLOW.
